UNITED STATES PATENT OFFICE.

WILLIAM J. EICHENBERG, OF TOLEDO, OHIO, ASSIGNOR TO INDUSTRIAL RESEARCH CORPORATION, OF TOLEDO, OHIO, A CORPORATION OF DELAWARE.

DRIVING MECHANISM.

Application filed July 22, 1918. Serial No. 246,135.

To all whom it may concern:

Be it known that I, WILLIAM J. EICHENBERG, a citizen of the United States, residing at Toledo, county of Lucas, and State of Ohio, have invented certain new and useful Improvements in Driving Mechanism, of which I declare the following to be a full, clear, and exact description.

This invention relates to a driving mechanism for use in the starting system of an internal combustion engine. More particularly considered, the invention comprises an automatic screw gearing applicable in the gear train intermediate the electric starting motor and internal combustion engine.

The principal object of this invention is to provide a driving mechanism intermediate the electric motor and engine, which has flexibility and elasticity, and in which there is no spring or similar elastic member in the direct line of power transmission.

Another object is to provide a type of gearing in which the driving connection and disconnection is made in an entirely automatic way.

Another object is to utilize a gearing unit which will automatically take care of variations in engine cylinder compression.

Further objects, and objects relating to economies of manufacture and details of construction will definitely appear from the detailed description to follow.

I accomplish the objects of my invention by the devices described in the following specifications. My invention is clearly defined and pointed out in the appended claims.

A device constituting a preferred embodiment of my invention is illustrated in the accompanying drawing, forming a part of this specification, in which:—

Figure I is a longitudinal section taken through the screw gearing, illustrating the various driving parts in disconnection;

Figure II is a part longitudinal section taken through the resilient portion of the

gear, and showing the various parts of the gear in driving relationship; and

Figure III is a cross section taken through the gearing along the lines III—III of Figure I.

Similar reference numerals refer to similar parts throughout the several views, and the cross section is taken looking in the direction of the small arrows.

As illustrated in the drawing, there is shown a portion of the frame work of an electric starting motor 1, which is of a type found most suitable for the performance of the starting function, relative to internal combustion engines. The motor has a driving shaft 2, upon which is mounted a cylindrical sleeve 3. This sleeve has a threaded portion 4, and a smooth portion 5, the threaded portion being on the end of the sleeve adjacent the motor, and these portions are separated from each other by an annular flange 6, which is integral with the sleeve. On the interior of the threaded portion of the sleeve, a key-way 7 is cut, and a key 8, secured in the motor shaft, is adapted to have sliding engagement in the key-way 7. The key-way slot extends to the inner end of the sleeve, so that the sleeve may readily be assembled upon the shaft. Rigidly secured to the motor shaft, adjacent the motor, is a cup-shaped stop 9, the edges of which extend outwardly along and parallel with the shaft, so that a portion of the inner part of the sleeve is enveloped.

The outer terminal of the motor shaft is threaded to receive a terminal washer 11, having shallow internally bent edges 12. In order to provide resiliency to the gearing, a coil spring 13 is utilized, which extends around the motor shaft intermediate the cup-shaped washer 11, in which one end of the spring is adapted to seat, and the annular flange. Normally, this spring exerts a pressure against the flange walls, thus forcing the sleeve which is longitudinally slideable in its key-way, to the extreme inner position, the inner end of the sleeve con-

tacting with the base of the cup-shaped stop 9.

As previously noted, the sleeve has an outer smooth portion which has a diameter less than that of the inner diameter of the coil spring 13, so that upon compression of the spring by movement of the sleeve outwardly, this portion has free movement along the motor shaft until it makes engagement with the terminal washer 11.

Mounted upon the threaded portion of the sleeve, is an internally threaded pinion 14, which is adapted to have longitudinal movement along the motor shaft, into engagement with the gear 15. Ordinarily, in order to assist the pinion in its operation, it is formed with a counter-weight 16, for a specific purpose hereinafter to be described. The gear 15 is directly connected to the crank shaft of the internal combustion engine, and takes the form, ordinarily, of the fly-wheel of the engine.

In the actual operation of the device, the power drive is from the motor shaft, through the sleeve pinion and gear, to the crank shaft of the internal combustion engine. The normal disconnected position is as shown in Figure I of the drawing. When the motor is started with its shaft in rotation as indicated by the small curved arrow, the sleeve rotates with the motor shaft, and the pinion through its inertia, and with the assistance of the unbalanced counter-weight, screws inwardly upon the sleeve without rotation, until it comes into complete enmeshment with the gear wheel 15. In this position, the inner end of the pinion is in contact with the outer edges of the stop 9, and since this stop is rigidly mounted upon the motor shaft, further inward motion of the pinion is completely prevented.

If there were no resilient elements in the mechanism, the pinion would immediately tend to take on the rotational speed of the sleeve and motor shaft, and because of the great inertia of the engine, disastrous effects such as stripping of the gear teeth would usually result. Through the employment of the coil spring, however, when the lateral movement of the pinion is stopped, the sleeve immediately begins to screw on the threaded pinion, forcing itself outwardly against the expansive force of the spring 13, until the outer end of the sleeve comes into engagement with the terminal washer 11. By this means, part of the rotational force of the motor is absorbed in the compression of the spring, so that the starting force is applied gradually to the load gear, and breakage due to the sudden jar of starting, which would otherwise result, is obviated.

It should be noted further, that the necessary parts are very limited, and that these parts can be assembled with great ease.

I am aware that the particular embodiment of my invention herein shown and described, is susceptible of considerable variation, without departing from the spirit of the invention, and, therefore, I desire to claim the same broadly as well as specifically as indicated by the appended claims.

Having thus described my invention, what I claim as new and desire to secure by Letters Patent, is:—

1. A starting mechanism for internal combustion engines, comprising in combination, a gear operatively connected to an engine; a starter shaft; a sleeve mounted on said shaft so as to have axial movement only relative to the shaft, said sleeve having a threaded portion and a smooth portion, and an integral annular flange between the threaded and smooth portions; a washer on the shaft; a spring inserted on said shaft intermediate the washer and said flange; and a pinion having threaded engagement with the threaded portion of the sleeve and adapted to make automatic engagement and disengagement with said gear, said smooth sleeve portion being adapted to form a positive driving connection to the starter shaft.

2. A starting mechanism for internal combustion engines, comprising in combination, a gear operatively connected to an engine; a starter shaft; a sleeve mounted on said shaft so as to have axial movement only relative to the shaft, said sleeve having a threaded portion and a smooth portion and an integral annular flange between the threaded and smooth portions; a stop on one end of said shaft; a washer on the other end of said shaft; a spring inserted on said shaft intermediate the washer and said flange; and a pinion having a threaded engagement with the threaded portion of the sleeve and adapted to move automatically into engagement with said gear and said stop, said smooth sleeve portion being adapted to form a positive driving connection between the sleeve and starter shaft.

3. In a starting mechanism for internal combustion engines, the combination of a gear operatively connected to an engine, a starter shaft; a cup-shaped stop fixed to one end of the shaft; a threaded sleeve on the shaft mounted to have axial movement only relative thereto, said sleeve having its end lying normally in the recess formed by the walls of said stop; a spring on said shaft operative to oppose axial movement of said sleeve; and a pinion threadably mounted on said sleeve adapted to move automatically into operative relation with said engine gear and into contact with said stop, whereby said gear may move the sleeve axially against the expansive force of the spring.

4. In a starting mechanism for internal combustion engines, the combination of a gear operatively connected to an engine, a starter shaft, a stop fixed to one end of said

shaft and having an over-hanging portion extending parallel to but separated from the shaft, a threaded sleeve on the shaft mounted to have axial movement only relative thereto, said sleeve having its end extending normally between the shaft and the over-hanging portion of said stop, resilient means to oppose axial movement of said sleeve away from said stop, and a pinion

threadedly mounted on said sleeve adapted to move automatically into operative relation with said engine gear and into contact with said stop, whereby said gear may move the sleeve axially against said resilient means. 15

In testimony whereof, I affix my signature.

WILLIAM J. EICHENBERG.
